[57] ABSTRACT

A method for forming a phonograph record jacket is provided. The method includes the steps of synchronously feeding two blanks of sheet material toward a registration location. One of the sheets includes a major rectangular portion and minor strip portions extending from and parallel to the longitudinal edges of the major portion. Prior to reaching the registration locations, these strips are folded back and an adhesive is applied thereby forming glue flaps which are joined to the other blank when the two blanks synchronously arrive at the registration location. A spine is simultaneously formed in the joined blanks substantially bisecting the longitudinal axis of the joined blanks and dividing the joined blanks into a record jacket having two adjacent pockets. If desired, one of the pockets may be sealed by adhesively joining the panels of the two blanks forming the one pocket.

METHOD OF FORMING PHONOGRAPH RECORD JACKET

BACKGROUND OF THE INVENTION

In my copending application, Ser. No. 333,962, filed Feb. 20, 1973, there is disclosed an improved record jacket formed from two blanks of sheet material in place of the unitary blank commonly used for such purposes. The present application relates to a method or process for economically and efficiently producing such jackets.

It is the principal object of the present invention to provide a method for producing two-piece record jackets which lends itself to mass production techniques so as to render such jackets competitive pricewise with conventional one-piece jackets. A further object of this invention is to provide a method by which two-pocket jackets are normally produced but which, with minor modification, can be used to produce a one-pocket jacket.

SUMMARY OF THE INVENTION

The above and other beneficial objects and advantages are attained in accordance with the present invention by providing a method for forming a phonograph record jacket from two blanks of sheet material. The method includes the steps of feeding a first blank of sheet material along a first path of travel toward a registration location. The first blank comprises two side by side, generally square panels comprising a major rectangular portion and minor strip portions extending from and parallel to the longitudinal edges of the major portion. A second, elongated, rectangular blank of sheet material is synchronously fed along a second path of travel to arrive at the registration location at the same time as the first blank. The minor strip portions of the first blank are folded over to form glue flaps prior to the first blank arriving at the registration location. When the two blanks meet, they are joined by an adhesive previously applied to the flaps of the first blank engaging the second blank along the longitudinal edges. A pair of spaced apart score lines are then simultaneously formed in both blanks substantially bisecting the longitudinal axes of the blanks. Construction of the jacket is then completed by folding the joined blanks along the score lines to form a spine for the record jacket and to form two pockets, each pocket defined by half of each of the blanks, a pair of sealed, opposed edges defined by the glue flaps, a closed edge defined by the spine and an open edge opposite the spine. If desired, additional adhesive can be applied to close one of the pockets thereby resulting in a single-pocket jacket.

BRIEF DESCRIPTION OF THE DRAWINGS

In the accompanying drawings:

FIG. 1 is a diagrammatic drawing of the steps followed in forming a two-pocket record jacket in accordance with the present invention; and,

FIG. 2 diagrammatically illustrates the additional step which may be practiced in accordance with the alternate method of the present invention to produce a single-pocket jacket.

DETAILED DESCRIPTION OF THE PRESENT INVENTION

A record jacket in accordance with the present invention is formed by feeding a first blank of sheet material 10 and a second blank of sheet material 12 along different paths of travel toward a common registration location generally designated by the reference numeral 14. The blanks 10 and 12 may be preprinted, die cut,

10 and, as pointed out in my copending application, one or both of them may be especially treated such as by coating with a foil, flocking, or the like. It is not necessary that both blanks 10 and 12 be formed of the same material.

15 Blank 12 is generally rectangular in shape with its length being twice its width and its width being substantially equal to the diameter of the record to be contained within the finished jacket. The length of blank 10 is substantially equal to that of blank 12. However, 20 the width of blank 10 is somewhat larger than that of blank 12. In this regard, blank 10 includes a central, rectangular, major portion 16 and a pair of minor strip portions 18 and 20 which extend from and parallel to the longitudinal axis of the major portion. It is to be noted that the dimensions of major portion 16 are substantially equal to those of blank 12. That is, the length of the major portion is substantially twice the width.

25 As blank 10 moves toward the registration location 14, a pair of notches 22 and 24 are cut into each of the strips 18 and 20 substantially bisecting the strips. Score lines 26 and 28 are then drawn across blank 10 at the base of the notches defining the longitudinal edges of the major portion of blank 16. As the first blank moves toward the registration location, the strips 18 and 20 are folded back over the major portion defining glue flaps 30, 32, 34 and 36. An adhesive 38 is then applied to each of the flaps. As previously mentioned, the second blank 12 is fed to the same registration location along a different path of travel designated by arrow 40. 30 The first and second blanks arrive at the registration location 14 synchronously and the second blank is adhesively secured to the first blank by the adhesive 38 on glue flaps 30, 32, 34 and 36. The two joined blanks 40 42 then move together along a third path of motion away from the registration location.

45 Blank 12 is formed of two, substantially square, side by side panels 44 and 46 and the major portion 16 of blank 10 is similarly constructed. After the joined blank 42 moves away from the registration location 14, a pair of spaced apart, parallel score lines 48 and 50 are formed across the joined blanks substantially bisecting the blanks and separating them into their panels. The open, free edges 52 and 54 are then trimmed and the selvage 56 removed. The assembly is completed by folding the trimmed joined blanks along the score lines 48 and 50 through two 90° bends to form spine 58 and thereby produce the desired jacket 60.

50 As will be noted, jacket 60 has two pockets 62 and 64, each designed to receive a record. The pockets are each defined by the spine 58, sealed top and bottom edges, and open side edge through which the record can be inserted and removed. It is often desirable to form a jacket with only a single pocket. This may be accomplished in accordance with the present method by 55 including the step illustrated in FIG. 2 of applying additional adhesive 66 to one of the panels of blank 16 prior to the blanks reaching the registration location 14.

Thereafter, when blank 12 is superimposed over blank 16, the corresponding panel of blank 12 will adhere to the panel containing the adhesive thereby sealing one of the pockets. It should be apparent that the adhesive 5 may be applied to either of the panels 68 or 70 of blank 16 as required for the desired finished jacket.

Thus, in accordance with the above, an improved method for the construction of phonograph record jackets is disclosed. It should be apparent to one familiar with the art that slight modifications in my method 10 may be employed without departing from the invention as set forth in the accompanying claims.

Having thus described the invention, what I claim is:

1. A method for forming a phonograph record jacket 15 comprising the steps of:

- a. feeding a first blank of sheet material along a first path of travel toward a registration location, said first blank comprising a major rectangular portion and minor strip portions extending from and parallel to the longitudinal edges of said major portion;
- b. synchronously feeding a second blank of sheet material along a second path of travel to arrive at said registration location at the same time as said first 25 blank;
- c. folding said minor strip portions of said first blank back over parts of said major portions whereby to form glue flaps prior to said first blank reaching said registration location;
- d. adhesively joining said second blank to the glue flaps of said first blank when said two blanks reach said registration location and removing said joined blanks from said registration location along a third path of travel;
- e. forming at least one score line substantially bisecting each of said joined blanks longitudinally; and,
- f. folding said joined blanks along said score line whereby to form a spine dividing said jacket into 40 two pockets, each pocket defined by said spine, two, closed opposite edges and an open, side edge.

2. The method in accordance with claim 1 wherein two, spaced apart, score lines are simultaneously 45 formed in said joined blanks substantially bisecting each of the blanks and said spine is formed by folding

said joined blanks 90° about each of said score lines.

3. The method in accordance with claim 1 further comprising the step of trimming the transverse edges of said joined blanks prior to forming said spine.

4. The method in accordance with claim 1 further comprising the step of notching each of said strips at substantially the longitudinal midpoint thereof prior to folding said strips over the major portion of said first blank to form said glue flaps.

5. The method in accordance with claim 1 further comprising the steps of preprinting each of said blanks prior to feeding said blanks toward said registration location.

6. A method for forming a phonograph record jacket comprising the steps of:

- a. feeding a first blank of sheet material along a first path of travel toward a registration location, said first blank comprising a major rectangular portion and minor strip portions extending from and parallel to the longitudinal edges of said major portion;
- b. synchronously feeding a second blank of sheet material along a second path of travel to arrive at said registration location at the same time as said first blank;
- c. said first and second blanks each having first and second side by side substantially square panels;
- d. folding said minor strip portions of said first blank over parts of said major portions thereof whereby to form glue flaps prior to said first blank reaching said registration location;
- e. adhesively joining said second blank to the glue flaps of said first blank when said two blanks reach said registration location and adhesively joining a first panel of said first blank to a first panel of said second blank when said two blanks reach said registration location and removing said joined blanks from said registration location along a third path of travel;
- f. forming at least one score line substantially bisecting each of said joined blanks longitudinally, and
- g. folding said joined blanks along said score line whereby to form a spine dividing said jacket into two parts, one of said parts including a pocket defined by said spine, two closed opposite edges and an open side edge.
